SKI BIKE

Morris Aubrey Elliott, Baltimore, Md.

Application April 9, 1946, Serial No. 660,634

5 Claims. (Cl. 280—16)

1

This invention relates to vehicles and more particularly to those of ski bike type for primarily gliding over snow and ice landscapes.

Devices of this nature have the general disadvantage of riding hard and on soft snow to sink deeply therein. This induces considerable friction which in turn tends to reduce their speed. The position of the center of gravity of the devices is not given much consideration, except to make sure that it falls within the area of the base when in normal position. It may be at any point of its length, also the individual centers of gravity of the sleds can come anywhere likewise in their length, depending on how the sleds happen to be made and on the material from which they are formed. This makes the balance of the device uncertain and its control harder to manipulate.

It is an object of this invention to provide a new and improved ski bike that will avoid one or more of the disadvantages and limitations of the prior art.

Another object of the present invention is to provide a new and improved ski bike that will travel over snow with relative facility unimpeded by the snow, even if moderately soft, and which has its balance so distributed as to make it convenient to use and manipulate by the operator and afford greater safety to the rider.

For a better understanding of the invention and other objects thereof reference is made to the appended drawings and the following description thereof which illustrate a form of the invention by way of example, while the scope and spirit of the invention is particularly pointed out in the claims.

In the drawings:

Figure 1 is a plan view of a ski bike embodying this invention;

Figure 2 is a side elevation of Figure 1, and

Figure 3 is a sectional view taken along line 3—3 of Figure 2.

Similar reference characters refer to similar parts throughout the drawings.

In this invention, the ski bike comprises a frame consisting of a straddle bar 10 of metal tubing bent arcuately for about half its length at the rear from a straight tangential section 13 that connects angularly with the front steering column 11. The straddle bar 10 supports on its upper surface a relatively long sitting board 12. This board is flat and attached to the section 13 and its front end portion 14 cut semi-circularly and terminating adjacent the column 11. Its rear portion 15 is squared and projects

2

rearwardly beyond the point where the arcuate contour meets the tangential section 13. The lower end 16 of the straddle bar is connected to the wide ski shoe 17. A connecting bar 18 of metal tubing is connected at one end close to the point where the lower end 16 meets the ski shoe 17. The bar 18 has a vertically offset contour with its opposite end attached to the slanting steering column 11 at a point 22 substantially located above the lower hinged end portion 19 of steering post 33. The shoe 17 is of relatively flexible construction so it can bend under unusual stresses towards the rear. Its front half is mounted on the connecting bar 18 and conforms to its bent offset portion at 20. A spread T-handle 30 is provided at the upper end of the steering post 33 and is used by the operator for guiding the ski bike. A set of foot rests 21 are connected at right angles on both sides of the steering post 33 about half way between the hinge at 19 and the location 22.

A front flat ski-shoe 23 is oscillatable on the hinge 19 at its bracket 24 mounted at its middle. The shoe 23 is flat for the greater portion of its length but its front end portion 25 is rounded quadrantly. The shoes 17 and 23 are reinforced underneath with ribs 26 and 27 respectively along their center lines for about one half the length of the respective shoes, and distributed longitudinally along them as indicated in the drawings. The shoes are made relatively wide to balance them more effectively and present a larger area over the snow on which they are intended to ride. The rear portion 28 of the shoe 17 is arcuately tapered to facilitate turning of the device on the snow.

More specifically the front ski-shoe 23 is mounted on the hinge 19 an inch or so in back of its center of gravity. The purpose of this is to provide a larger supporting area ahead of the hinge. This induces a tendency in the shoe to ride higher in front than its rear. This gives the ski-shoe a continually climbing out reaction on the snow. The frontwardly curved under portion 29 of the steering post 33 and the displacement of the hinge 19 with respect to the center of gravity referred to, permits a quicker balance regain in the device when riding over the snow. In other words, the operator is given better control of the ski-bike.

In making a left turn, the rider's body is deliberately thrown off balance to the left of the center of gravity. To counteract this out-of-balance condition, the rider instinctively turns the ski to the left in order to bring the bottom

section of the bike back under, or, in line with, the center of gravity. A turn thereby results. The act of regaining balance will be quickened when the hinge is set forward from the center of the steering column. When the rider turns the ski to the left, there is a corresponding movement of the ski sidewise to the left. This sidewise movement of the ski forms the arc of a circle, the radius determined by the distance between the front hinge pin and the center of the steering column. The front ski-shoe 23 is about one sixth longer than the rear ski-shoe 17 because the distribution of the weight of the device with the operator on it is greater on it. The weight thrown on the front shoe 15 packs the snow in front and provides more effective purchase for the shoe when turning. If the weight is thrown on the rear shoe 17 instead, the steering of the front ski-shoe 23 would have an inappreciable turning effect on the ski bike. The rear shoe 17 is attached to fittings 36 which form part of bar 18.

The front half of the rear ski-shoe is mounted solidly to the frame. The rear half of the rear ski-shoe is flexible. This flexibility prevents "dig-in" when the front end of the bike is rising to a high plane. A rigid rear ski will always dig-in. A movement such as that obtained by using a hinge is also undesirable on the rear ski because it would actually contribute a steering action that would be uncontrollable. If, for instance, the ski-mobile in a turn and the rear ski-shoe were permitted the free movement of a hinge, a downward or upward movement would actually cause the whole rear end of the bike to move from side to side. If the device were in a left turn and the front of the rear ski-shoe moved downward, the tendency would be for the rear of the ski-mobile to move to the right. This would only increase the difficulty of getting it back into balance.

The flexibility of the material of the rear ski-shoe 13 provides a smoothly running ski bike. Instead of digging-in the snow, during its travel, the shoe bends up out of the way. An extra passenger or the original operator can stand on the wide rear ski-shoe 13 and maintain the balance of the device effectively.

The seat is long to make it adaptable for various types of users and positions they may wish to take. The foot rests are attached to the steering post 33 and afford convenience to coasting. The foot rests are so located on the steering column as to permit the operator to steer the device from them with his feet, instead of by the handle.

While but one general form of the invention is shown in the drawings and described in the specifications, it is not desired to limit this application for patent to this particular form or in any other way otherwise than limited by the scope thereof, as it is appreciated that other forms of construction could be made that would use the same principles and come within the scope of the appended claims.

Having thus described the invention; what is claimed is:

1. A ski bike comprising in combination, a steering post, a straddle bar, a connecting bar, a front column having said bars connected at one end in T-form thereto, a rear ski-shoe having 70 fittings which are attached rigidly to the connecting and straddle bars, said fittings and rear ski shoe closely following the contour of said connecting bar, said shoe having an extending portion flexibly arranged to allow the rear end of

the shoe to adjustably adapt itself to the terrain on which its rides, a front ski-shoe hinged to the lower end of said steering post at an off-center portion of said front ski-shoe to permit a front-riding lifting action in this shoe in conformity with the terrain, and means for guiding said ski-bike.

2. A ski bike comprising in combination, a steering post, a straddle bar, a connecting bar, a front column having said bars connected at one end in T-form thereto, a rear ski-shoe having fittings which are attached rigidly to the connecting and straddle bars, said fittings and rear ski shoe closely following the contour of said connecting bar, said shoe having an extending portion flexibly arranged to allow the rear end of the shoe to adjustably adapt itself to the terrain on which it rides, a front ski-shoe hinged to the lower end of said steering post at an off-center portion of said front ski-shoe to permit a front-riding lifting action in this shoe in conformity with the terrain, means for guiding said ski-bike, said means being operable by the hands and feet of the operator using the ski bike.

25 3. A ski bike comprising in combination, a steering post, a straddle bar, a connecting bar, a front column having said bars connected at one end in T-form thereto, a rear ski-shoe having fittings which are attached rigidly to the connecting and straddle bars, said fittings and rear ski shoe closely following the contour of said connecting bar, said shoe having an extending portion flexibly arranged to allow the rear end of the shoe to adjustably adapt itself to the terrain on which it rides, a front ski-shoe hinged to the lower end of said steering post at an off-center portion of said front ski-shoe to permit a front-riding lifting action in this shoe in conformity with the terrain, means for guiding said ski-bike, said means being operable by the hands and feet of the operator using the ski bike.

30 4. A ski bike comprising in combination, a steering post, a straddle bar, a connecting bar, a front column having said bars connected at one end in T-form thereto, a rear ski-shoe having fittings which are attached rigidly to the connecting and straddle bars, said fittings and rear ski shoe closely following the contour of said connecting bar, said shoe having an extending portion flexibly arranged to allow the rear end of the shoe to adjustably adapt itself to the terrain on which it

35 rides, a front ski-shoe hinged to the lower end of said steering post at an off-center portion of said front ski-shoe to permit a front-riding lifting action in this shoe in conformity with the terrain, means for guiding said ski-bike, said means being operable by the hands and feet of the operator using the ski bike, means extending longitudinally on the straddle bar for seating the operator in various locations on the ski-bike.

5. A ski bike comprising in combination, a steering post, a straddle bar, a connecting bar, a front column having said bars connected at one end in T-form thereto, a rear ski-shoe having fittings which are attached rigidly to the connect-

ing and straddle bars, said fittings and rear ski shoe closely following the contour of said connecting bar, said shoe having an extending portion flexibly arranged to allow the rear end of the shoe to adjustably adapt itself to the terrain on which it rides, a front ski-shoe hinged to the lower end of said steering post at an off-center portion of said front ski-shoe to permit a front-riding lifting action in this shoe in conformity with the terrain, means for guiding said ski-bike, said means being operable by the hands and feet of the operator using the ski bike, means extending longitudinally on the straddle bar for seating the operator in various locations on the ski bike, said straddle bar having an arcuate rear section with its front section extending tangentially therefrom to said column, and the steering post curved forwardly to the front ski-shoe where it attaches thereto and where the off-center point is in back of the center of gravity of 20

said last mentioned shoe, the rear ski having its front portion upwardly curved and its front section rigidly connected with said connecting bar.
